(57) **CLAIM**

The ornamental design for an edge terminal device, as shown and described.

DESCRIPTION

FIG. 1 is a top perspective view of the edge terminal device, showing the new design;

FIG. 2 is a front elevational view of the edge terminal device;

FIG. 3 is a top plan view of the edge terminal device; and, FIG. 4 is a right side elevational view of the edge terminal device, the left side elevational view being a mirror image thereof.

The broken line remainder of the edge terminal device is for illustrative purposes only and forms no part of the claimed design.
